INVENTOR:
John Reinhart
BY *Wm F. Trendenreich*
ATTORNEY

UNITED STATES PATENT OFFICE.

JOHN REINHART, OF CHICAGO, ILLINOIS.

PAPER-HANGER'S STRAIGHTEDGE.

Application filed February 7, 1923. Serial No. 617,441.

To all whom it may concern

Be it known that I, JOHN REINHART, a citizen of the United States, residing at Chicago, county of Cook, State of Illinois, have 5 invented a certain new and useful Improvement in Paper Hangers' Straightedges, and declare the following to be a full, clear, and exact description of the same, such as will enable others skilled in the art to which it 10 pertains to make and use the same, reference being had to the accompanying drawing, which forms a part of this specification.

The most satisfactory method of trimming the edges of wall paper so as to insure 15 that they will be perfectly straight, is to lay a straight edge on the paper to serve as a guide for the knife by means of which the paper is trimmed. Unless the straight edge be true the line of the cut will not be 20 straight, but all of the straight edges that I have ever seen used for this purpose have soon become warped or otherwise distorted, so that satisfactory results could no longer be obtained therewith.

25 The object of the present invention is to produce a straight edge built up in such a manner that it will retain its initial shape indefinitely, and the manufacturing cost of which shall be low enough to make the commercial use thereof practicable.

The various features of novelty whereby 30 my invention is characterized will hereinafter be pointed out with particularity in the claims; but for a full understanding of my invention and its objects and advantages, 35 reference may be had to the following detailed description taken in connection with the accompanying drawing, wherein:

Figure 1 is a plan view of one edge of 40 a straight edge, arranged in accordance with my invention;

Figure 2 is an edge view and Figure 3 an end view of the device; and

Figure 4 is an end view of a slightly modified form of straight edge.

Referring to Figures 1 to 3, 1, 2 and 3 represent the three plies or layers of a long narrow three-ply wooden panel which forms the body portion of my improved straight edge. Any desired number of plies may of course be used, but I have found three plies to serve very well for the construction of straight edges about three inches wide and five eighths of an inch thick, which is one of the sizes commonly used. The grain of the wood in the two outer layers runs in the

direction of the length of the panel, while the grain in the central layer is arranged crosswise. The several plies are glued together in any usual or suitable manner, either in sizes adapted to form single units or in sheets large enough to form a plurality of straight edge panels when cut up. Glued to each long edge of the central panel is a facing strip 4 of any desired width and preferably of the same or approximately the same thickness as the central panel.

Since these straight edges often become wet, either during use or because of the necessity of washing them I prefer so to make 70 the joints between the central panel and the facing strips that it will be practically impossible for the glue, even though it should not happen to be waterproof, to be affected sufficiently by moisture 75 to cause the strips to become loose. This can most conveniently be accomplished by forming the central panel with a longitudinal groove in each long edge, and providing the facing strips with tongues that enter 80 these grooves. In the arrangement shown, the grooves have a width equal to the thickness of the central layer or ply, so that the grooves are produced by simply making the central layer or ply narrower than the outer 85 layers. If the panels are built up as individual units, the central layer or ply may simply be made narrower than the two outer layers or plies, or it may be made the same width as the latter, the grooves being 90 afterwards formed by means of a suitable cutting tool. In any event, the central panel when finished, has grooves adapted to receive the tongues 5 on the facing strips.

The arrangement shown in Fig. 4 is similar to that just described, except that the central layer or ply of the panel or body of the device is formed out of a thick core 6 in which the grain extends crosswise, together with extremely thin facing layers 95 7 and 8 of veneer, in which the grain runs lengthwise. This form of central ply may be useful when individual panels are glued up one at a time, since it affords a simple way of securing the long strips of wood in 100 which the grain extends crosswise; the thin layers of veneer preventing the core strip 105 from breaking during the operation of building up the individual panels.

While I have illustrated and described 110 with particularity only a single preferred form of my invention, with a slight modifi-

cation, I do not desire to be limited to the exact structural details thus illustrated and described; but intend to cover all forms and arrangements which come within the 5 terms employed in the definitions of my invention constituting the appended claims.

I claim:

1. A straight edge comprising a long narrow central three-ply wooden panel in 10 which the grain in one ply extends transverse to the grain in the other two plies, the middle ply being narrower so as to produce a groove in each long edge of the panel, and facing strips extending along said edges of 15 the said panel and having tongues fitting into said grooves.
2. A straight edge comprising a long narrow three-ply wooden panel, the grain in the two outer plies extending in the direction of the length of the panel and the grain in the central ply extending crosswise of 20 the panel, the central ply being narrower

than the other plies so as to produce a groove in each long edge of the panel, and strips of solid wood of about the same thickness as the panel fitting against the long edges of the panel and having tongues fitting into said grooves. 25

3. A straight edge comprising a long narrow central 3-ply wooden panel in which the 30 grain of one ply extends transverse to the grain in the other two plies, the middle ply being narrower so as to produce a groove in each long edge of the panel, and facing strips extending along said edges of the panel and 35 having tongues fitted into and secured in said grooves, said facing strips having outer edges arranged at right angles to the board faces of said panel and at least as wide as the greatest thickness of said panel. 40

In testimony whereof I sign this specification.

JOHN REINHART
